CONVERSION AND COKING OF HYDRO-CARBON OILS

Joseph G. Alther, Chicago, Ill., assignor to Universal Oil Products Company, Chicago, Ill., a corporation of Delaware

Application July 29, 1932, Serial No. 625,865

1 Claim. (Cl. 196—49)

This invention particularly refers to an improved process and apparatus for the conversion and coking of hydrocarbon oils wherein heavy oils, tars and similar materials of high coke-forming characteristics which may be carried over or entrained by the vapors are separated from the vaporous products resulting from the coking operation, prior to fractionation of the vapors, and are returned directly to the coking chamber for further treatment.

By separating tars and other heavy coke-forming materials from the vaporous products of the process, prior to the separation of lower boiling oils or reflux condensate therefrom the return of such materials to the heating coil, together with the reflux condensate, is prevented, obviating the deposition of coke in the heating coil due to the decomposition of such materials therein. The invention also provides for the return of the heavy tar-like material separated from the vapors direct to the coking chamber of the process wherein they are reduced to coke by further treatment together with the fresh residual liquid products from the conversion zone of the system.

The adaption of the primary features of the invention is not limited to any specific form of process or apparatus as its features may prove advantageous in any type of coking system although they are especially well adapted to use in processes of the type wherein the conversion of hydrocarbon oil is accompanied by reduction of the residual liquid conversion products to coke, particularly at reduced pressure, and wherein insufficiently converted or intermediate conversion products of the operation are returned to further conversion in a heating coil of the same system.

The attached diagrammatic drawing illustrates one specific form of apparatus in which the process of the invention may be carried out. It should be borne in mind, however, that the apparatus here shown and described represents only one of the many types of apparatus in which the concept of the present invention may be applied.

Referring to the drawing, raw oil charging stock for the system is supplied through line 1 and valve 2 to pump 3 from which it is fed through line 4, valves 5 and 6, heat exchanger 7, line 8 and valve 9 to heating coil 10. Any other well known manner of supplying the raw oil charging stock to the system may, of course, be employed, when desired, although other means are not illustrated in the drawing.

Heating coil 10 is located within a furnace 11 of any suitable form by means of which the oil

supplied to the heating coil is heated to the desired conversion temperature preferably at a substantial super-atmospheric pressure. The heated oil is discharged from heating coil 10 through line 12 and, in the case here illustrated, passes 5 preferably through valve 13 in this line into the lower portion of reaction chamber 14 or may be diverted from line 12 through line 15 and valve 16 by means of which it is directed into the upper portion of reaction chamber 14. 10

Reaction chamber 14, like coil 10, is preferably maintained at a substantial super-atmospheric pressure by means of which the heated oil from heating coil 10, and more particularly its vaporous components, are subjected to continued conversion time in the reaction chamber. The chamber is preferably insulated by well known means, not shown in the drawing, to prevent the excessive loss of heat by radiation and thus maintain the vapors at a suitably high conversion 20 temperature during their passage through this zone.

When, as previously described, the heated oil from heating coil 10 is discharged into the lower portion of chamber 14 through line 12 and valve 13, separation of the major portion of the residual liquid conversion products from the vaporous conversion products is quickly effected and the residual liquid withdrawn from the lower portion of the reaction chamber through line 17 and valve 18 while still in a highly heated state, without being subjected to appreciable further conversion time in the reaction chamber, and is discharged at reduced pressure through line 19 into coking chamber 20. In this case the vaporous 25 conversion products separated from the residual liquid in the lower portion of the reaction chamber are subjected to continued conversion time as they pass upward through the chamber, being withdrawn from its upper portion through line 21 and preferably passing, as here illustrated, through valve 22 into the lower portion of coking chamber 20, although they may be introduced into the coking chamber at any desired point or may be commingled with the residual liquid, 30 prior to its introduction into the coking chamber or, when desired, may pass all or in part from the reaction chamber direct to fractionation by well known means not illustrated. 35

When the heated oil from heating coil 10 is introduced, as previously described, through line 15 and valve 16 into the upper portion of chamber 14, the vaporous conversion products, being lighter than the residual liquid, may pass downward through the chamber more slowly than 50

the residual oil, being thereby subjected to a longer conversion time in the reaction chamber than that afforded the residual liquid conversion products. In this case both vaporous and residual liquid conversion products having passed through chamber 14 are preferably withdrawn in commingled state through line 17 and valve 18 and directed through line 19 into the reduced pressure coking chamber 20.

In the case here illustrated, the latent heat liberated by the reduction of pressure in chamber 20, relative to that employed in chamber 14 assisted by the partial pressure effect of the vaporous products from the upper portion of chamber 14, passing upward through the body of residual oil in the coking chamber, as well as by any heat which the vapors may impart to the residual liquid, serves to reduce the residual liquid conversion products from chamber 14 to coke in chamber 20. It is, of course, within the scope of the present invention to employ any other well known means of insuring coking of the residual liquid conversion products in chamber 20 although, for the sake of simplicity, other means are not illustrated. The coking chamber may, for example, be externally heated or a suitable heat carrying medium, such as a light final or intermediate conversion product of the process or suitable light oil from an external source, heated to a high temperature may be introduced into direct contact with the material undergoing coking in the coking chamber. It is also possible to assist coking by the introduction of air or other oxidizing gas to effect partial combustion and increase the temperature in the coking zone or heated relatively inert gases such as hot combination gas may be supplied to the coking zone.

Coke is allowed to accumulate within chamber 20 to be removed therefrom after the operation of the chamber has been completed or, preferably, a plurality of coking chambers similar to chamber 20, but not illustrated in the drawing, are employed and may be alternately operated while a chamber previously filled with coke is being cleaned and prepared for further operation, thus providing an unlimited space for the deposition of coke. Chamber 20 is provided with a drain-line 23 controlled by valve 24 which may also serve as a means of introducing steam, water or other suitable cooling medium into the chamber, after it has been isolated from the system, to hasten cooling and permit cleaning of the tubes.

Vaporous products, including tars and similar high coke-forming materials vaporized under the coking conditions employed and/or carried over with the vapors by entrainment, are withdrawn from the coking chamber through line 25 and valve 26 to a tar-separator 27 wherein said heavy coke-forming materials are condensed and separated from the vapors. The tars and similar high coke-forming materials are withdrawn from the lower portion of separator 27 through line 28 and valve 29 to pump 30 by means of which they are returned through line 31, valve 32 and line 19 to coking chamber 20 for further heating and reduction to coke. They may of course be separately introduced into chamber 20 when desired by well known means which are not illustrated.

Vaporous products from the coking chamber substantially freed of heavy coke-forming materials in separator 27 are withdrawn from the upper portion of this zone through line 33 and

valve 34 to heat exchanger 7 wherein they are partially cooled by indirect contact and heat exchange with the oil being supplied to heating coil 10. Condensate resulting from cooling of the vapors in heat exchanger 7 is returned by means of line 35 and valve 36 to tar-separator 27 wherein it is substantially revaporized by direct contact with vaporous products from the coking chamber, serving as a means of cooling the vapors and effecting the condensation and removal of the heavy tars and similar high coke-forming materials therefrom.

The partially cooled vapors substantially freed of deleterious heavy materials pass from heat exchanger 7 through line 31 to fractionator 38 wherein their insufficiently converted components are condensed as reflux condensate. The reflux condensate removed from the vapors in fractionator 38 collects in the lower portion of this zone and is withdrawn therefrom through line 39 and valve 40 to pump 41 to be returned therefrom to heating coil 10 for further conversion. In the case illustrated, the reflux condensate is directed from pump 41 through line 42 and valve 43 into line 4, commingling therein with the raw oil charging stock from pump 3 and passing therewith through heat exchanger 7, line 8 and valve 9 to heating coil 10. It will be understood that the reflux condensate may, when desired, be returned to the heating coil in any well known manner not illustrated in the drawing. It is also within the scope of the invention to utilize a portion of the reflux condensate or a portion of the raw oil charging stock or a mixture thereof as a cooling medium in tar-separator 27, particularly in case heat exchanger 7 is not utilized or in case the condensate from this zone is not sufficient to effect the desired separation in tar-separator 27. Suitable means for the introduction of such materials into separator 27 are well known and are not here illustrated.

Fractionated vapors of the desired end-boiling point are removed, together with uncondensable gas, from the upper portion of fractionator 38 through line 44 and valve 45, are subjected to condensation and cooling in condenser 46, from which the resulting distillate and uncondensable gas passes through line 47 and valve 48 to receiver 49. Uncondensable gas may be released from receiver 49 through line 50 and valve 51. Distillate may be withdrawn from this zone through line 52 and valve 53. A portion of the distillate from receiver 49 may, when desired, be recirculated, by well known means not illustrated in the drawing, to the upper portion of fractionator 38 to serve as a cooling and refluxing medium in this zone, to assist in maintaining the desired vapor outlet temperature from the fractionator.

In a process of the character illustrated and above described, preferred operating conditions may be as follows:

Temperatures of 900 to 1,050° F., or thereabouts, may be employed at the outlet from the heating coil, preferably with a super-atmospheric pressure at this point ranging, for example, from 100 to 500 pounds, or thereabouts, per sq. in. Pressures within substantially this same range are preferred in the reaction chamber but the coking chamber, as well as succeeding portions of the system, is preferably maintained at a substantially reduced pressure relative to that employed in the reaction chamber, said reduced pressure ranging, for example, from 100 pounds, or thereabouts, per sq. in. down to substantially atmospheric pressure. Preferably the vaporous

products entering the fractionator of the system are cooled to a temperature of about 750° F. or less, in order to prevent the return of any appreciable amount of material boiling above this 5 temperature to the heating coil.

As a specific example of the operation of the process of the present invention, let us first consider an operation similar to that above described except that the features of the present invention 10 are not utilized. The raw oil charging stock is a 30° A. P. I. gravity Mid-Continent topped crude which is subjected together with the total reflux condensate, including heavy tars, from the coking operation to a conversion temperature of approximately 935° F. at a super-atmospheric pressure 15 of about 350 pounds per sq. in. Substantially this same pressure is maintained in the reaction chamber, residual liquid being quickly separated from the residual products in the reaction chamber 20 and withdrawn to alternately operated coking chambers maintained at a pressure of about 20 pounds per sq. in. while vaporous products separately withdrawn from the upper portion of the reaction chamber, are passed upward through the bed of residual material in the coking chamber. This operation may yield, per barrel of charging 25 stock, about 62 percent of motor fuel having an antiknock value equivalent to an octane number of approximately 74, the additional products of the process being about 90 pounds of coke and about 700 cubic ft. of uncondensable gas per barrel of charging stock. The process may be operated continuously over a period of from 2 to 3 weeks and is shut down, almost invariably, due to the 30 deposition of coke in the heating coil.

In another operation similar to that just described except that the features of the present invention are utilized and heavy tars are separated from the vapors, prior to their fractionation by cooling them to a temperature, measured 35

at the inlet to the fractionator, of about 730° F. and returning said heavy materials to the coking chamber, a temperature of about 950° F. may be safely employed at the outlet from the heating coil but the other operating conditions are maintained about the same as those above given. This operation may produce about the same yield of motor fuel, based on the raw oil charging stock, but its antiknock value may be increased to an octane number of approximately 78. A somewhat lower yield of coke of lower volatile content is produced as compared with the operation first described and the production of gas is slightly increased. In addition to the advantages of better antiknock motor fuel and lower volatile coke, 15 the improved process of the present invention permits an operating cycle 2 to 3 times as long as that possible when the features of the invention are not employed.

I claim as my invention:

A conversion process which comprises heating hydrocarbon oil to cracking temperature under pressure in a heating coil and then discharging the same into an enlarged separating zone, separating vapors from unvaporized oil in the separating zone, introducing the unvaporized oil to the upper portion of a coking still and distilling the same to coke in this zone, removing separated vapors from the separating zone and introducing the same to the lower portion of the coking still 20 to pass upwardly therethrough in countercurrent contact with the unvaporized oil, separating from the coke still vapors tars and similar high coke-forming materials and returning the same to the coking still without prior heating thereof to 25 cracking temperature, fractionating the remaining coke still vapors and supplying resultant reflux condensate to the heating coil, and finally condensing the fractionated vapors.

JOSEPH G. ALTHER. 40
